(57) CLAIM

The ornamental design for a spice rack, as shown and described.

DESCRIPTION

FIG. 1 is a top, front, right side perspective view of a spice rack;

FIG. 2 is a top, rear, left side perspective view of a spice rack;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The spice jars shown in broken lines depict environmental subject matter and form no part of the claimed design. The remaining broken lines shown in the figures depict portions of the spice rack that form no part of the claimed design.
